TREATMENT OF HYDROCARBON OILS

Jacque C. Morrell, Chicago, Ill., assignor to Universal Oil Products Company, Chicago, Ill., a corporation of South Dakota

No Drawing. Application June 6, 1931,
Serial No. 542,704

4 Claims. (Cl. 196—36)

This invention relates to the treatment of hydrocarbon oils and refers more particularly to the treatment of the relatively low boiling fractions resulting from the cracking of heavier hydrocarbons though similar distillates produced from noncracking distilling operations may also be treated.

In a more specific sense the invention has reference to the treatment of hydrocarbon oil fractions of the types mentioned with reagents adapted to reduce their content of unsaturated hydrocarbons and sulphur compounds, a process being hereinafter disclosed which possesses marked advantages over processes at present in vogue for producing similar results.

In its specific and preferred embodiment the invention comprises treatment of hydrocarbon oil vapors with pyrosulphates, or the salts of pyrosulphuric acid, e. g., the pyrosulphates of sodium, potassium or ammonium. It is also contemplated using mixtures of aqueous solutions of pyrosulphates and sulphuric acid. The use of possible pyrosulphates of the heavy metals is also contemplated.

As a result of extended researches in the different branches of the oil refining industries it has been definitely established that low boiling hydrocarbon distillates containing large amounts of fractions boiling within the range of commercial gasoline are composed of, in addition to hydrocarbons of a saturated nature such as paraffins and naphthenes, varying though usually minor portions of unsaturated hydrocarbons both of the straight chain and cyclic types. The unsaturated compounds, particularly those of the straight chain type, are characterized by a tendency to polymerize under the influence of light and air or other oxidizing agents to form high boiling resinous or tarry aggregates which color the distillates and depreciate the value of the gasoline produced therefrom both from the standpoint of selling and from the standpoint of its use as motor fuel. The sulphur content must usually be down to a certain limit value to correct undue corrosion effects. To reduce the percentage of the more reactive unsaturated and sulphur compounds mentioned and to render the derived motor fuels sufficiently stable has been the object of a large number of refining methods, the first and most generally used of which being the well known treatment with sulphuric acid of commercial grade, either alone or combined with other alkaline or sweetening treatments. The use of sulphuric acid, however, to selectively remove the more highly unsaturated olefins which are the principal "gum-formers" while leaving unaffected the mono-olefins which add to the antiknock value of the fuel without adding materially to the gum content, is attended with difficulty owing to the lack of complete selectivity of the acid in re-

spect to the separation mentioned. It is with improvements in the ordinary methods of treating gasoline distillates particularly cracked distillates, that the present invention is concerned, the use of the pyrosulphates mentioned affording a more selective and readily controllable treating method.

Persulphuric acid of the formula $H_2S_2O_7$ may be considered as a compound between one molecule of water and two molecules of sulphur trioxide, and corresponding to a sulphuric acid containing 45% free sulphur trioxide by weight. It is a crystalline solid melting at 35° C., the melting point being lowered either by the addition of sulphur trioxide or water. Numerous salts of this acid have been prepared, the most common of which are those of sodium and potassium, these being best prepared by the action of sulphur trioxide upon their anhydrous normal sulphates. Sodium pyrosulphate $Na_2S_2O_7$ has a melting point of 400° C. and a density of 2.66. The melting point of the potassium salt is slightly higher being 414° C. while its density is slightly lower, that is, 2.51. In addition to the two simple salts mentioned the existence of the following double salts has been confirmed:

$2Na_2SO_4 \cdot 9H_2SO_4$	$Na_2SO_4 \cdot 2H_2SO_4$
$Na_2SO_4 \cdot H_2SO_4$	$Na_2SO_4 \cdot 3H_2SO_4$
$K_2SO_4 \cdot H_2SO_4$	$(NH_4)_2SO_4 \cdot 3H_2SO_4$
	$(NH_4)_2SO_4 \cdot H_2SO_4$

While treatment of cracked vapors by pyrosulphates may be effected in a variety of ways, a few will be mentioned as indicating the wide applicability of these compounds. A convenient method of use consists in incorporating the salt to be used with spacing or adsorbent material such as fuller's earth and other earthy and relatively inert materials and placing the finely divided composite mass in a tower or column through which the vapors may pass upwardly or downwardly depending upon operating conditions encountered such as, for example, the quantity and type of sludge formed. The melting points of the salts most commonly employed, that is, those of sodium, potassium and ammonium are considerably above the temperatures of fractionated cracked vapors as they are encountered in practice but the melting point of the sludges produced in some cases is sufficiently lower to permit their flow under conditions of operation in vapor phase treatments, so that the reaction products may be more or less continuously removed from the spacing material as liquid during the operation of the process. It is within the scope of the invention to employ a number of treating towers in parallel so that cracked vapors from any source may be continuously treated, a tower containing fresh treating reagent being cut in as other towers become spent.

Treatments of cracked vapors may also be conducted in towers or columns containing no filling material by injecting finely divided composite particles containing pyrosulphates into the upper portions of such towers so that they gradually settle downwardly through the rising steam of vapors and effect a countercurrent treatment, the sludge-coated particles being removed from the bottom of the tower either intermittently or continuously by the use of suitable mechanical devices such as belt or screw conveyors.

Solutions of pyrosulphates, preferably aqueous solutions may be employed by countercurrent or concurrent treatment of the hydrocarbon vapors.

It is also within the scope of this invention to mix solutions of pyrosulphates with sulphuric acid as a treating agent. It is to be understood that the solids and solution will vary somewhat in degree of treating effect produced as well as results and hence are not to be considered as precise equivalents.

Temperatures and pressures employed in such vapor phase treatments as have been described above may be determined to some extent by the pressures and temperatures existing in the fractionating equipment from which the vapors are produced though at times such temperatures and pressures may need to be reduced in order to minimize undesirable side reactions resulting from the tendency of the pyrosulphates to oxidize when temperature and pressure conditions are permitted to attain a certain degree of severity. The temperature of cracked vapors from the primary fractionating equipment of cracking processes are commonly included within the range of 250 to 550° F. and the pressures are commonly from 100 to 500 pounds per square inch. To effect final fractionation for the production of vapors of approximate gasoline boiling point range the pressure is frequently reduced to below 100 pounds per square inch with a corresponding drop in temperature due to adiabatic expansion.

Use of pyrosulphates in the treatment of cracked vapors is most advantageously preceded by alkaline or metallic treatments to remove hydrogen sulphide and a certain amount of highly reactive sulphur derivatives though this is not absolutely essential to the efficient operation of the process. The use of these salts may also be followed by the addition of ammonia to neutralize traces of residual acidic compounds and the further passage of the vapors through filter beds to remove minor amounts of entrained reaction products.

The degree and nature of treating effects produced may be readily controlled by selection of the particular salt to be used and the amount of inert material with which it is incorporated as well as by the manipulation of pressure and temperature and the use of upward and down flow, etc. At times the double salts mentioned in the preceding paragraph or combinations of salts may be used and also salts of less basic elements than the sodium and potassium and other alkali metals.

As an example of results obtainable by the use of the process of the invention a case involving the treatment of the vapors from the cracking of a mixture composed of 50% of Mid-Continent residuum and 50% of a heavy gas oil may be con-

sidered. The vapors from a cracking plant operating on such a blend at approximately 250 pounds per square inch and a temperature of 935° F. may be fractionated in a secondary fractionator under the reduced pressure of approximately 75 pounds per square inch to produce a fraction with a final boiling point of approximately 400° F. which if condensed and given no other treatment than a light caustic wash may have the following approximate characteristics:

Gravity	55.5	80
Mgs. gum by copper dish method	400	
Sulphur	0.25%	
Color	Pale yellow	90

By treating the vapors with fuller's earth containing 10% by weight of sodium pyrosulphate so that approximately 6 pounds of the salt are consumed per barrel of condensate and following this treatment by proper neutralization and washing to remove traces of entrained reaction products, the gasoline finally condensed may have the following properties as compared with the above:

Gravity	55.8	100
Gum	20-25 mgs.	
Color	+30	
Sulphur	0.1%	

A comparison of the properties of the raw gasoline with the gasoline produced by treating according to the process of the invention will readily indicate the advantages to be gained by the use of the process. Similar results may be obtained with Californian and other charging stocks. It will be noted also that the amount of sodium pyrosulphate used by weight is approximately equal to the weight of sulphuric acid which would ordinarily be employed in liquid phase treatment of the raw gasoline prior to its rerunning to produce a finished product. However, since the percentage of sulphur trioxide in sodium pyrosulphate is only 36% compared with 81.6% in sulphuric acid it will be evident that the treating effects in the present instance are produced by the use of considerably lessened amounts of acidic material.

The improvements in treating process constituting the present invention will be obvious from the preceding descriptive material and example but the points covered are more or less descriptive and illustrative and the particular details disclosed are not to be considered as constituting a limitation upon the generally broad scope of the invention.

I claim as my invention:

1. A process for refining hydrocarbon distillates which comprises, subjecting said distillate in heated vaporous condition to the action of an aqueous solution of a pyrosulphate.

2. A process for refining hydrocarbon distillates which comprises, subjecting said distillate in heated vaporous condition to the action of an aqueous solution containing a pyrosulphate and sulphuric acid.

3. A process for refining hydrocarbon distillates which comprises, subjecting said distillate in heated vaporous condition to the action of an aqueous solution containing a pyrosulphate.

4. A process for refining hydrocarbon distillates which comprises, subjecting said distillate in heated vaporous condition to the action of an aqueous solution containing a pyrosulphate of an alkali metal.

JACQUE C. MORRELL.
